JEWELRY DISPLAY RACK

Robert D. Joyce, Gloucester, R.I., assignor to Richton
International Corporation, New York, N.Y.

Filed Jan. 29, 1973, Ser. No. 327,756

Term of patent 14 years

Int. Cl. D20—02

U.S. Cl. D6—139

FIG. 1

FIG. 2

FIG. 3

FIG. 4

FIG. 5

FIG. 6

FIG. 1 is a front elevational view of a jewelry display rack having my new design;

FIG. 2 is a front elevational view showing the rack of FIG. 1 in expanded position;

FIG. 3 is a rear elevational view of the rack shown in FIG. 1;

FIG. 4 is a side elevational view thereof;

FIG. 5 is a top plan view thereof; and

FIG. 6 is a bottom plan view thereof.

I claim:

The ornamental design for a jewelry display rack, substantially as shown.
